COMBINATION PIPE STAND AND ASH TRAY

Leo K. Lindzy, Wayne, Mich.

Application November 21, 1947, Serial No. 142,713

Term of patent 7 years

(Cl. D85—8)

To all whom it may concern:

Be it known that I, Leo K. Lindzy, a citizen of the United States, residing at Wayne, in the county of Wayne and State of Michigan, have invented a new, original, and ornamental Design for a Combination Pipe Stand and Ash Tray, of which the following is a specification, reference being had to the accompanying drawing, forming part thereof in which,

Fig. 1 is a perspective view of a combination pipe stand and ash tray, showing my new design,

Fig. 2 is a side elevational view of a combination pipe stand and ash tray showing my new design,

Fig. 3 is an end elevational view of a combination pipe stand and ash tray.

I claim:

The ornamental design for a combination pipe stand and ash tray, as shown.

LEO K. LINDZY.
